CLAIM

The ornamental design for a dental x-ray sensor, as shown and described.

DESCRIPTION

FIG. 1 is a top right perspective view of a dental x-ray sensor showing my new design;

FIG. 2 is a bottom left perspective view thereof;

FIG. 3 is a front view thereof, projected from the right side of FIG. 7;

FIG. 4 is a rear view thereof, projected from the left side of FIG. 7;

FIG. 5 is a top view thereof;

FIG. 6 is a bottom view thereof; and,

FIG. 7 is a right side view thereof, the left side view being a mirror image thereof.

The wire jacket of the dental x-ray sensor has been shaded to indicate the color gray.

1 Claim, 2 Drawing Sheets
